UNITED STATES PATENT OFFICE.

CALVIN B. PATCH, OF CHICAGO, ILLINOIS, ASSIGNOR, BY MESNE ASSIGNMENTS, TO
WILLIAM H. MINER, OF CHICAGO, ILLINOIS.

CAR-DOOR FASTENER.

968,190.

Specification of Letters Patent. Patented Aug. 23, 1910.

Application filed October 30, 1909. Serial No. 525,431.

To all whom it may concern:

Be it known that I, CALVIN B. PATCH, a citizen of the United States, residing in Chicago, in the county of Cook and State of Illinois, have invented a new and useful Improvement in Car-Door Fasteners, of which the following is a specification.

My invention relates to improvements in car door seal fasteners.

10 My invention consists in the novel construction of parts and devices and in the novel combinations of parts and devices herein shown and described and more particularly specified in the claims.

15 In the accompanying drawing forming a part of this specification, Figure 1 is a front elevation of a pair of refrigerator car doors provided with my improved invention. Fig. 2 is a detail perspective view showing 20 the doors closed and sealed. Fig. 3 is a perspective view showing the members of the fastener disengaged and Fig. 4 is a detail vertical section of the staple member of the fastener.

25 In the drawing, A represents a portion of a refrigerator car, B B the refrigerator car doors, C the hinges thereof, D the operating shaft for opening and closing the refrigerator car doors, E the keepers secured to the 30 car frame or upper and lower sills of the door frame, F the hasp lever member of the fastener, G the staple member of the fastener, H the swinging latch or lock on the staple member and K the sealing strip or 35 loop.

The door closing and opening shaft D and coöperating keeper E may be of any suitable kind or construction adapted to open and close the refrigerator car doors. The 40 operating shaft D is preferably journaled in suitable brackets D¹ on one of the doors near the free edge thereof and is preferably provided with integral crank arms d at its upper and lower ends adapted to engage the 45 inclined or wedging faces E¹ E² of the keepers E to force the doors snugly and tightly closed and to force the doors open, when the operating shaft is turned first in one direction to close the doors and then in 50 the opposite direction to force them open. The operating shaft D is also provided with a short lever arm d¹ to which the hasp lever F is hinged by a pin or rivet d² so that the

hasp lever may swing down out of the way parallel to the operating shaft when the 55 doors are unlocked or unfastened.

The hasp lever F is preferably furnished with jaws f fitting each side the short lever arm d¹ of the operating shaft D, and it is provided with a slot f¹ to receive the staple 60 G when the doors are forced closed by turning the operating shaft D with the hasp lever. The hasp lever F is provided preferably with a bent handle f² at its end.

The staple member G, if the car is furnished with two doors closing together as illustrated in the drawing, is secured to the outer face of one of the doors by suitable bolts g extending through the face plate g¹ of the staple member. The staple member 70 G is provided with a locking recess g² to receive the curved end h of the swinging lock or latch H which is pivotally secured to the staple member G, preferably by an integral hollow pivot stud g³ on the staple 75 member, the outer end of which is upset or riveted over the swinging latch or lock H to pivotally secure the lock to the staple member. The locking shoulders g⁴ formed on the staple member G by the recess g² 80 therein serves to securely hold the hasp lever in place on the staple G and prevents strain from coming upon the sealing wire or strip K which is inserted through suitable registering openings g⁵ in the staple and h¹ in the 85 swinging latch or lock H.

The seal strip or loop K is furnished with the customary seal device or rivet K¹ of soft metal and adapted to be upset with the sealing punch so as to prevent tampering of the 90 lock or fastener without detection.

I claim:—

1. A refrigerator car door fastener comprising an upright shaft mounted on the door and having crank arms at its ends, 95 keepers on the door frame adapted to engage said crank arms, a hasp lever secured to said rotary shaft and having a slot, a staple member having a locking shoulder and provided with a swinging latch pivoted thereto directly above said shoulder and adapted to engage said locking shoulder and hold the hasp lever in place on the staple, substantially as specified.

2. The combination with a door frame 105 having keepers secured thereto, of a door

having an operating shaft furnished with crank arms engaging said keepers and provided with an operating arm, a hasp lever secured to said operating arm, a staple member having a staple and provided with a recess to receive the free end of a swinging latch pivoted to said staple member above

said staple and a swinging latch for holding the hasp lever in engagement with the staple, substantially as specified.

CALVIN B. PATCH.
